UNITED STATES PATENT OFFICE.

JAMES S. PATES, OF MONONGAHELA, PENNSYLVANIA.

COAL-TIPPLE.

No. 863,313.

Specification of Letters Patent.

Patented Aug. 13, 1907.

Application filed January 18, 1907. Serial No. 352,915.

To all whom it may concern:

Be it known that I, JAMES S. PATES, a resident of Monongahela, in the county of Washington and State of Pennsylvania, have invented certain new and useful 5 Improvements in Coal-Tipples, of which the following is a specification.

Coal tipples now in general use are provided each with a holding bar which is pivoted to and depends from the rear end of the tilting platform and coöperates 10 with a holding device on the tipple structure for controlling the upward movement of the platform, being operated either as a brake for causing the platform to move slowly, or for arresting its movement altogether. When the platform is tilted this bar is elevated through 15 the car approach, and it is not infrequent for cars to move toward the platform when the latter is raised, bumping into and breaking the bar, as heretofore no means have been provided for protecting the bar from such a blow. In fact the danger of breaking bars is 20 so great that it is a common practice to have a supply of bars in reserve for each tipple, in readiness to replace those which are broken.

One object of the present invention is to provide for a cushioned movement or play of the bar in the direction of movement of an approaching car, so that it may 25 not only withstand the blow of a car, but also stop its forward movement.

A further object of the invention is to provide for cushioning the shock incident to the sudden stopping 30 of the car when it reaches its position on the tilting platform. Injury to the tipple, and particularly the operating portion of the mechanism, is thereby avoided. This feature of the invention is preferably embodied in cushioned or yielding bearings in which the tilting 35 platform oscillates, thus cushioning the tilting mechanism in its entirety. This cushioning of the platform also coöperates in a measure with the bar-cushioning mechanism for yieldingly resisting the blow upon the latter of an approaching car.

40 Still a further object of the invention is to provide improved mechanism for operating the car-holding stops or horns.

In the accompanying drawings, Figure 1 is a side elevation, partially broken away, of a tipple constructed 45 in accordance with the invention. Fig. 2 is a cross-sectional view on line 2—2 of Fig. 1. Fig. 3 is a view on a larger scale of the bar holding and cushioning mechanism, and Figs. 4 and 5 are detail views of portions of the latter. Fig. 6 is a detail view of one of the 50 platform bearings. Fig. 7 is a top plan view of the tilting platform, and Fig. 8 is an inverted plan view of the same.

55 Referring to the drawings, 2 designates the outside longitudinal timbers of the tipple structure, upon which are mounted the bearing slideways 3 in which

are slideable bearings 4 for trunnions 5 of the tilting platform 6. The bearings are held normally in the rear ends of the slideways by springs 7, the latter being confined each by a bolt 8 secured to the bearing and extending through one end of slideway 3 where it is 60 provided with nut 8'. By this means the tension of the springs may, if desired, be regulated. Connected to platform 6 are the usual cross-over rails 9.

A tongue 10 extends rearward from the center of the platform, and overhangs the tipple approach. Pivoted at 10' to this tongue is the depending curved bar or sword 11, formed on its opposite edges with the alternately arranged stops or holding points 12 which co-operate with a movable holding device. This portion of the apparatus, as here embodied, is in accordance 70 with reissue Letters Patent No. 12,553, granted to me November 6th, 1906.

Bar 11 operates through a casing 14, here shown secured to intermediate timber 2' of the tipple frame. This casing is constructed with two horizontal passages 75 or slideways—one above the other. A slide 15 is movable in the upper guide-way, being formed with a passage 15' for bar 11. This slide is reciprocated against the pull of spring 16 for engaging it with first one and then another of bar stops 12 for intermittently and suddenly stopping the ascent of the bar, and thus jolting the tilting platform for the purpose of shaking the coal from the car, all as described in my Letters Patent 80 above referred to. Slide 15 may be conveniently operated by link 17 connecting it to an arm 17' of rock 85 shaft 18, the latter carrying the upright operating lever 18'.

In the lowermost slideway of casing 14 is guide 19 having a vertical passage which in shape corresponds to the cross-section of bar 11, and as I prefer to form the 90 bar with side ribs 11', the passage in the guide has corresponding offsets 19'. One end of the guide is provided with a depending lug 20, and a heavy spring 21 is confined on tension regulating bolt 21' between this lug and the outer face of casing 14, thus holding the 95 guide normally fixed, but permitting it and the bar to move forward when the latter is bumped by an approaching car. The shock is thus arrested and the bar afforded such a compensating movement as to save it from injury in many cases where otherwise it would be 100 broken. This movement of the guide does not interfere in any way with the operation of the bar-holding mechanism.

It is characteristic of the horn-operating mechanism of the present invention that it is all mounted on and 105 movable with the tilting platform. I am aware that this is not broadly new, and claim novelty only for the improved arrangement of operating parts. The horns or car stops 22 each consists of a horizontal body portion having at one end the raised wheel-engaging por- 110

tion 23. The stop is mounted between its ends on a vertical pivot 24, with the end opposite the car-holding end connected by link 25 with the inner end of bar 26, the latter being movable longitudinally of and secured 5 to the under side of the platform 6. A spring 27 is connected to links 25 and normally holds the horns in car stopping position, with a stop 28 limiting the movement imparted by the spring. The forward end of bar 26 is connected to the lower end of vertical lever 29, the 10 latter being fulcrumed between its ends to the extremity of tongue 10, and at its upper end carrying wheel 30. This wheel is adapted to be engaged by the under portion of a car approaching the tilting platform and is rocked forward, thus operating the mechanism 15 which connects with the pivoted horns in such a manner as to turn the latter and release the previously emptied car and permit it to pass on to cross-over rails 9 as the next car passes onto the platform.

The platform with the emptied car may be lowered 20 from tilted position by means of a power cylinder 31, having its piston connected by line 32 with the platform.

I claim:

1. In a tipple, the combination of a tilting platform, a bar depending from the platform, bar-holding means, and means for cushioning the bar against lateral pressure.
2. In a tipple, the combination of a tilting platform, a bar depending therefrom, bar-holding means, and means for cushioning the bar against the blow from a car approaching the platform.
3. In a tipple, the combination of a tilting platform, a bar depending from the platform, bar-holding means through which the bar moves as the platform raises and lowers, and cushioning means for yieldingly holding the bar against lateral pressure.
4. In a tipple, the combination of a tilting platform, a bar depending from the platform, bar-holding means, and a yielding guide for the bar.
5. In a tipple, the combination of a tilting platform, a bar depending from the platform, bar-holding means, a slideable guide for the bar, and cushioning means for resisting the sliding of the bar.
6. In a tipple, the combination of a tilting platform, a bar depending therefrom, bar-holding means, a fixed casing and formed with a horizontal slideway, and a guide through which the bar moves vertically, said guide being movable in the slideway, and a spring for resisting the movement of the guide.
7. In a tipple, the combination of a tilting platform, a toothed bar depending therefrom, a holding device for en-

gaging the bar teeth, and cushioning means for yieldingly holding the bar against lateral pressure.

8. In a tipple, the combination of a tilting platform, a toothed bar depending therefrom, a holding device movable horizontally for engaging the bar teeth, said holding device having a vertical passage for the bar, a movable guide for the bar, and cushioning means for the guide.

9. In a tipple, the combination of a tilting platform, a toothed bar depending therefrom, a casing formed with two horizontal slideways—one above the other, a holding device movable horizontally in one of the slideways for engaging the bar teeth, a guide movable in the other slideway, the holding device and guide having a vertical passage through which the bar moves, and means for cushioning the movement of the guide.

10. In a tipple, the combination of a tilting platform, and means for affording the platform a cushioned movement independently of its tilting movement.

11. In a tipple, the combination of a tilting platform, movable bearings therefor, and means for cushioning the movement of the bearings.

12. In a tipple, the combination of a tilting platform, movable bearings therefor, and means for cushioning the bearings against the blow of a car passing onto the platform.

13. In a tipple, the combination of a tilting platform, slideways on the tipple structure, bearings for the platform movable in the slideways, and springs for resisting the movement of the bearings.

14. In a tipple, the combination of a tilting platform having spring resisted movement in the direction of an approaching car, and car stopping devices on the platform unyieldingly held in operative position.

15. In a tipple, the combination of a tilting platform, car holding stops pivotally mounted on the platform, a bar carried by and movable longitudinally of the platform, laterally-extending links pivoted at their inner ends to said bar and at their outer ends to said stops, means for moving the bar longitudinally, and a spring for resisting said movement.

16. In a tipple, the combination of a tilting platform, car-holding stops, each of said stops being mounted between its ends on a vertical pivot, a bar movable longitudinally of the platform, laterally extending links pivoted at their inner ends to the bar and at their outer ends to the ends of the stops opposite the car holding ends of the latter, said bar extending in the direction of the car approach, means actuated by an approaching car for moving the bar, a spring for resisting such movement, and a stop for limiting the movement imparted by the spring.

In testimony whereof I affix my signature in presence of two witnesses.

JAMES S. PATES.
